ICE BLOCK STORAGE AND DISPENSING RACK

Harold O. MacLean, Highland Park, Ill.

Application July 30, 1953, Serial No. 371,294

7 Claims. (Cl. 193—39)

The present invention relates generally to an ice block storage rack, but more particularly to a novel and improved master type of ice storage and dispensing rack for the storage and dispensing of thousands and thousands of tons of ice blocks so as to have the ice blocks readily available for the continuous and instant supply of ice blocks for various purposes such as the prompt and uninterrupted supply of ice blocks for the continuous operation of icing machines in connection with ice servicing of refrigerator cars at icing docks or stations.

Heretofore it has been the practice, in connection with the icing or ice servicing of refrigerator cars at icing stations, to employ sufficient labor to transfer manually one ice block at a time from the ice warehouse or ice storage house to an adjacent ice block conveying belt for the purpose of conveying and supplying ice blocks to the icing or ice servicing machines, with the result that there were not only interruptions in the continuous supply of ice blocks but also a large crew of men were required to perform this function. This method of operation was not only inefficient and expensive but also resulted in long delays in icing or ice servicing of refrigerator cars.

It is therefore, not only one of the primary objects of the present invention to overcome the objections or disadvantages hereinabove pointed out, but to also provide a compact ice block storage and dispensing rack which is adapted to be mounted within the conventional ice block warehouse or ice storage building where it is instantly available to supply a continuous flow of ice blocks to the icing machines without any interruptions and with the employment of the minimum number of men.

A further object of the invention is to provide a novel and improved construction of ice block storage and dispensing rack which includes two spaced apart ice block storage spirals, having a plurality of ice block channels extending therebetween and arranged in tiers and in substantial alignment with one another.

A still further object of the invention is to provide a novel and improved ice block storage and dispensing rack in which a series of manually controlled gates located at points adjacent to the entrances and exits of the ice block channels controls the passage of the ice blocks to and from the channels and spirals.

A further object of the invention is to provide a novel and improved construction of ice block storage and dispensing rack in which the delivery end of the rack is provided with a primary control gate for dispensing the ice block onto a main ice block conveyor.

These and other objects are accomplished by providing a construction and an arrangement of the various parts in the manner hereinafter described and particularly pointed out in the appended claims.

Referring to the drawings:

Fig. 1 is a top plan view, on a considerably reduced scale, showing my improved ice block storage and dispensing rack;

Fig. 2 is a side elevational view of the same;

Fig. 3 is an enlarged fragmentary top plan view of the

2

left hand spiral as viewed in Figs. 1 and 2 of the drawing showing the manner in which channels of one tier are connected to the spiral;

Fig. 4 is an enlarged fragmentary top plan view of the right hand end as viewed in Figs. 1 and 2.

Fig. 5 is an enlarged fragmentary cross-sectional view taken on the lines 5—5 in Fig. 3 of the drawings;

Fig. 6 is an enlarged fragmentary top plan view showing the construction of the main discharge gate;

10 Fig. 7 is an enlarged elevational view of the same;

Fig. 8 is a cross-sectional view taken on the lines 8—8 in Fig. 3;

Fig. 9 is an enlarged fragmentary top plan view taken on the lines 9—9 in Fig. 10 of the drawings; and

Fig. 10 is an enlarged cross sectional view taken on the lines 10—10 in Fig. 9 of the drawings.

In illustrating one embodiment of my improved ice block storage and dispensing rack, I have shown the same as comprising two or more spaced ice block spirals generally indicated by the reference characters 10 and 11 which are connected together and communicate with one another by a plurality of slightly inclined block conveying channels arranged in a tier and are generally indicated by the reference character 12.

25 This ice block storage and dispensing rack is adapted to be mounted within the building or walls of an ice storage or warehouse diagrammatically indicated at 13. The channels 12 are arranged in longitudinal parallel alignment and are also arranged in parallel vertical tiers and each set of channels are generally indicated at 14 to 23 inclusive.

30 Starting from the top, each successive set of the tier of channels are connected to and communicate at one end with a circular portion of the spiral 11 and at the other end with the next lower circular portion of the spiral 10, so that there is sufficient inclination in the channels to feed or move by gravity the ice blocks toward the dispensing end of the ice block rack.

35 Each of the spirals 10 and 11 are channel-like in cross-section and comprise a bottom plate 24 and opposite inner and outer circular walls 25 and 26 respectively. Three suitably spaced apart ice block guide tracks 27 are secured to the bottom plate 24 to facilitate the travel of the ice blocks 28 therealong. See Figs. 3 and 8. The spirals 10 and 11 are supported by suitably spaced and vertically disposed channel posts or frame members 29 which have their lower ends secured in the floor of the storage housing 13 in any suitable manner.

40 Each of these sets of channels indicated at 14 to 23 inclusive consists of a plurality of longitudinally extending troughs or channels indicated at 1', 2', 3', 4', 5', 6', 7', 8', 9', and 10'. These troughs 1' to 10' inclusive include a bottom 30 and side walls 31. The bottom 30 is provided with a plurality of spaced apart guide tracks 55 32 so as to facilitate the free passage of the ice blocks throughout the entire length of the channels. See Figs. 2 and 5.

45 Located at proper intervals between the channels and at different elevations in the tier, are suitable catwalks 60 generally indicated at 33, 34 and 35, so that access to the channels by an operator may be readily accomplished.

50 All the channels 1' to 10' inclusive of the entire tier 14 to 23 inclusive are supported in position by a plurality of spaced apart vertical posts or frame members 36 and transverse horizontal frame members 37. The frame members 37 are secured to the post members at vertical 65 spaced intervals of sufficient elevations so as to freely accommodate the passage of the ice blocks in their respective channels. The sets of channels 14 to 23 inclusive are identical in construction except that each successive set is located at a different elevation and therefore

a detailed description of the set 14 will suffice for all the sets of the tier.

Referring to Fig. 3 of the drawings it will be noted that channel 1' of the top set 14 is connected to a diagonally disposed delivery channel 38 which has its delivery end extending tangent to and communicating with the top circular portion of the spiral 10 for delivering ice blocks from channels 1', 2', 3' and 4'. In other words, the diagonal channel 38 serves as a common conveying trough for each of the channels 1' to 4' inclusive by means of control gates hereinafter described. The ice blocks in these channels 1' to 4' inclusive can be discharged into the spiral 10. In this connection it will also be noted that the delivery ends of channels 2', 3', 4' and 5' all converge in a direction toward one side of the spiral 10. See Figs. 1 and 3. An arcuate gate 38' pivoted at 37' controls the discharge of ice blocks from the channel 1' and the common channel 38 into the top circular portion of the spiral 10. A gate 39 pivoted at 40 on the vertical wall 31 between the channels 1' and 2' controls the movement of ice blocks from the channel 2', to the common channel 38. A gate 41 pivoted at 42 controls the ice blocks from channel 3' to channel 38. A stationary wall 43 forms a portion of the wall of the channel 38 diagonally across the lower end of the catwalk 33. Another gate 44 pivoted at 45 on the vertical wall adjacent the catwalk 33 controls the movement of ice blocks from the channel 4' to the common channel 38. Another gate 46 pivoted at 47 to the vertical wall 31 between the channels 4' and 5' controls the movement of ice blocks from the channel 5' to the spiral 10. Another gate 48 pivoted at 49 to the vertical wall 31 adjacent the catwalk 34 controls the movement of ice blocks from the channel 6' to a diagonal extension channel 50 of the channel 5'. Another gate 51 pivoted at 52 to the vertical wall 31 between the channels 6' and 7' controls the movement of ice blocks from the channel 7' to the channel 50. Another gate 53 pivoted at 54 controls the ice blocks in channel 8'. A vertical stationary section or wall 55 forms a portion of the channel 50. A gate 56 pivoted at 57 controls the discharge of ice blocks at the delivery end of the channel 9' into the end of channel 10' and an arcuate gate 59 pivoted at 60 controls the discharge of ice blocks from the channels 9' and 10' to the spiral 10.

In a very similar manner the channels 1' to 10' inclusive are loaded with ice blocks from the loading spiral 11. An ice block elevating mechanism, not shown, elevates the ice blocks to a receiving channel 61 which extends tangent to the topmost circular portion of the spiral 11 where the ice blocks are received for discharging them into the channels 1' to 10' inclusive. An arcuate gate 62 pivoted at 63 controls the entrance of ice blocks into channel 1'. A gate 64 pivoted at 65 controls the entrance to channel 2'. A gate 66 pivoted at 67 controls the entrance of ice blocks to channel 3'. An arcuate gate 68 pivoted at 69 controls the entrance of ice block into the diagonal channel 70 which is an extension of channel 10' and communicates with channels 7' to 10' inclusive or extensions thereof. Gate 71 pivoted at 72 controls the entrance of ice block into extension 73 of channel 6'. Gate 74 pivoted at 75 controls the entrance to channel 4' from the extension channel 73. Gate 76 pivoted at 77 controls the entrance to channel 5' from extension channel 73. Gate 78 pivoted at 79 controls the entrance to channel 7'. Gate 80 pivoted at 81 control the entrance of ice blocks to channel 8', and gate 82 pivoted at 83 controls the entrance to channel 9'.

As hereinbefore pointed out my improved ice block storage and dispensing rack is loaded by elevating the ice blocks onto the receiving channel 61 where they are discharged into the top circular portion of the spiral 10 and travel by gravity to the bottommost circular portion of the spiral 10. From this lowermost portion the ice blocks are then discharged into the channels 1' to

10' inclusive of the lower set of channels 23, the proper manipulation of the gates controlling the entrance to these channels. In other words, all the channels of the complete tier are loaded by filling the lowermost set 23, then 22 and then on upwardly to the top. In this connection it will also be noted that the both spirals 10 and 11 can be completely loaded from the top circular portion to the bottom thereof so that when the rack is completely filled to six hundred tons or more, they will be ready for the instant dispensing of ice blocks in a continuous and uninterrupted flow to the main conveyor, which in turn, supplies the ice to the ice servicing machines for icing or servicing refrigerator cars.

In order to illustrate and describe in more detail the manner in which the various gates are constructed and operated, I have shown a section of the device in Figs. 9 and 10. In these figures vertically disposed stationary rods 85, 86 and 87 extend through the aligned channels and form pivots for the gates of all of the channels. These rods pivotally support tubular crank shafts 88, 89 and 90. Each of the tubular crank shafts have right angularly projecting slotted crank arms 91 which, in turn, are connected to the piston ends of conventional hydraulic cylinder units indicated generally by the reference character 92. These cylinder units are supported on brackets 93 which are secured to the next adjacent channel bottom 30 of the set of channels above. In the case of the topmost set 14, suitable cross frame members may be provided for supporting these hydraulic units. It will, of course, be understood that in each case the gates for example 48, 51 and 53 are rigidly attached to tubular shafts 90, 89 and 88 respectively, so that upon the actuation of the hydraulic units the gates will open or close. In this connection it will also be noted that a control or operator's station on the ground will be provided. This control station will be provided with suitable electrically controlled buttons which will control the valves for the individual hydraulic units. The energization of the hydraulic units can be controlled so as to individually actuate the gates located at any point throughout the storage rack. The movement therefore of the ice blocks may be controlled from one point, preferably of a station adjacent the discharge end of the spiral 10.

Referring to 1,5 and 6 of the drawings, it will be noted that I have provided an ice dispensing channel 94 which extends tangent to the lower most round of the spiral 10. This channel 94 controls dispensing of the ice blocks directly from the storage rack to the main ice block conveyor leading to the ice servicing machines. This dispensing channel is provided in one of its walls 97, with a control gate or stop 95, which is positioned in the rectangular opening 96 located in one of the side walls 97 of the channel 94. This gate 95 is secured to a crank shaft 98 which in turn is pivoted in spaced apart brackets 99 secured to one of the side walls 97 of the channel 94. A conventional hydraulically actuated unit, 100, is operatively connected to the crank shaft 98 for actuating the same. The unit 100 is mounted in a bracket 101 secured to the side wall 97 adjacent to crank 98. Positioned adjacent and between the free end of the gate or stop 95 are two spaced apart springs, 102, which have outer ends seated as shown in 103, in an offset bracket 104, secured to the side frame 97. The other ends of the springs engage lugs 105 on the gate 95. These springs normally urge the stop or gate 95 inwardly and assist the hydraulic unit to control the flow of ice blocks 28 therethrough. The hydraulic units as previously pointed out can be controlled by the operator at the station from which he is capable of controlling all the gates throughout the storage rack.

Summarizing the advantages and functions of operation of my improved ice block storage and dispensing rack, it will be readily understood that by storing six

hundred tons or more of ice blocks in a plurality of channels between the two spaced apart spirals, a continuous uninterrupted supply of ice blocks may be dispensed from the rack and continuously conveyed to the icing machines so that there is no delay in icing or ice servicing the refrigerator cars at the icing stations. It will also be noted that this construction of an ice block storage and dispensing rack reduces the number of men heretofore required for transferring ice blocks from the ice storage building to the main ice block conveyor.

While in the above specification I have illustrated and described two spaced apart spirals 10 and 11 with connecting channels arranged in tiers, it will, of course, be understood that additional spirals or additional channels may be added to those illustrated without departing from the spirit and scope of the invention.

While I have described one embodiment which my invention may assume in practice in the above specification, it will, of course, be understood that the same is capable of modification and that modification may be made without departing from the spirit and scope of the invention as expressed in the following claims.

What I claim as my invention and desire to secure by Letters Patent is:

1. An ice block storage and dispensing rack comprising two spaced apart spirals of channel-like cross-section for storing and conveying ice blocks therein, a plurality of longitudinally extending ice block conveying channels extending between each successive round of each spiral, the channels of each successive round located in a vertical tier, and means located adjacent the ends of said channels for controlling the entrance and discharge of ice blocks to and from said channels.

2. An ice block storage and dispensing rack comprising two spaced apart spirals of channel-like cross-section for storing and conveying ice blocks therein, a plurality of longitudinally extending ice block conveying channels extending between each successive round of each spiral, the channels of each successive round located in a vertical tier, and gates located at the entrances and exits of said channels for controlling the passage of ice blocks to and from said channels.

3. An ice block storage and dispensing rack comprising two spaced apart spirals of channel-like cross-section for storing and conveying ice blocks therein, a plurality of longitudinally extending ice block conveying channels extending between each successive round of each spiral, the channels of each successive round located in a vertical tier, certain of said longitudinal channels extending in a direction tangent to said spirals, and gates located in the path of movement of the ice blocks for controlling their movement.

4. An ice block storage and dispensing rack comprising two spaced apart spirals of channel-like cross-section for storing and conveying ice blocks therein, a plurality of

longitudinally extending ice block conveying channels extending between each successive round of each spiral, the channels of each successive round located in a vertical tier, certain of said longitudinal channels extending in a direction tangent to said spirals, certain other of said channels converging toward other of said channels, and gates located in the path of movement of the ice blocks for controlling the movement of the ice blocks.

5. An ice block storage and dispensing rack comprising a spiral frame for the storing and conveying of ice blocks, a second spiral frame spaced from the first frame, a plurality of inclined ice block conveyor frames extending between said spirals for storing and conveying ice blocks from one spiral to the other spiral, gates for controlling the discharge of ice blocks from one spiral to said inclined frames, gates for controlling the discharge of ice blocks from the inclined frames to the other of said spirals, and individual hydraulic units operatively connected to each of said gates for actuating said gates.

6. An ice block storage and dispensing rack comprising a spiral frame for storing and conveying ice blocks, a second spiral frame spaced from the first frame, a plurality of inclined channel frames extending between said spiral frames and arranged at a slight inclination to the horizontal, said channel frames arranged in a vertical tier, gates pivoted to said channels adjacent the entrances and exits thereof for controlling the movement of ice blocks therein, and hydraulic units operatively connected to the individual gates for actuating the same.

7. An ice block storage and dispensing rack comprising a spiral frame for storing and conveying ice blocks, a second spiral frame spaced from the first frame, a plurality of inclined channel frames extending between said spiral frames and arranged at a slight inclination to the horizontal, said channel frames arranged in a vertical tier, gates pivoted to said channels adjacent the entrances and exits thereof for controlling the movement of ice blocks therein, vertical shafts extending through said channels, crank shafts secured to said gates and journaled on said vertical shafts, and means carried by said channels and operatively connected to said crank shafts for actuating said gates.
